COMBINED SCRAPER AND BRUSH

Irving W. Jorgensen, Owosso, Mich.

Application June 27, 1958, Serial No. 51,570

Term of patent 14 years

(Cl. D9—6)

Fig. 1 is a perspective view on a reduced scale of a combined scraper and brush showing my new design;

Fig. 2 is a similar perspective view of the opposite side and end thereof, with the scraper element telescoped into the frame of the brush element;

Fig. 3 is a top plan view of the combined brush and scraper;

Figs. 4 and 5 are elevational views of the two sides thereof;

Fig. 6 is an end elevation thereof taken from the right of Fig. 4;

Fig. 7 is a sectional view on the line 7—7 of Fig. 4; and

Fig. 8 is a fragmentary cross section on the line 8—8 of Fig. 4.

In Figs. 1, 2 and 5, portions of the brush element are omitted for convenience of illustration only.

I claim:

The ornamental design for a combined scraper and brush, as shown and described.
